UNITED STATES PATENT OFFICE.

HAROLD H. WILL, OF SYRACUSE, NEW YORK, ASSIGNOR TO THE WILL & BAUMER CO., OF SYRACUSE, NEW YORK, A CORPORATION OF NEW YORK.

DESIGN FOR A CANDLE.

50,671.

Specification for Design.

Patented Apr. 24, 1917.

Application filed August 29, 1916. Serial No. 117,546. Term of patent 14 years.

To all whom it may concern:

Be it known that I, HAROLD H. WILL, a citizen of the United States, residing at Syracuse, in the county of Onondaga and State of New York, have invented a new, original, and ornamental Design for a Candle, of which the following is a specification, reference being had to the accompanying drawing, forming a part hereof.

In the drawing, Figures 1 and 2 are respectively top plan and elevation of a candle of my design.

This design for a candle comprises seven surfaces *a* of substantially equal width extending lengthwise of the body of the can-

dle, contiguous portions of each pair of these surfaces *a* meeting in like obtuse angles, and a plurality of concentric surfaces *b* at the top of the candle, the surfaces *b* of lesser diameter being raised above those of greater diameter.

I claim:

The ornamental design for a candle, substantially as shown and described.

In testimony whereof, I have hereunto signed my name, at Syracuse, in the county of Onondaga, and State of New York, this 9th day of June, 1916.

HAROLD H. WILL.
